INVENTOR.
Napoleon R. Rivers,

BY

Irving L. McCallum
ATTORNEY.

UNITED STATES PATENT OFFICE

NAPOLEON R. RIVERS, OF ASHTABULA, OHIO

WRENCH

Application filed April 2, 1928. Serial No. 266,797.

This invention relates to the class of tools and pertains particularly to a wrench.

The primary object of the present invention is to provide, in a manner as hereinafter set forth, a wrench of a design capable of being quickly adjusted to take an article of any size within certain limits, without the necessity of manipulating holding devices of any character.

10 Another object of the invention is to provide, in a manner as hereinafter set forth, a quick adjustable wrench in the make up of which there are no removable parts or parts to be manipulated, thereby giving a tool 15 which, because of the ease with which it can be adjusted to take a nut or similar article and because of the fact that there are no parts to be lost, will greatly expedite the performance of working operations.

20 A still further object of the invention is to provide a wrench of the above described character which will be strong and durable, and comparatively inexpensive to manufacture and set up.

25 The invention will be best understood from a consideration of the following detailed description taken in connection with the accompanying drawing forming a part of the present invention, with the understanding, 30 however, that the invention is not confined to any strict conformity with the showing of the drawing but may be changed or modified so long as such changes or modifications mark no material departure from the salient features of the invention as expressed in the appended claim.

In the drawing:

Figure 1 shows the wrench structure embodying the present invention in side elevation.

40 Figure 2 is a side elevational view of the wrench showing the same opened to its fullest extent.

45 Figure 3 is a view in edge elevation of the wrench structure.

Figure 4 is a sectional view taken substantially upon the line 4-4 of Figure 3.

50 Figure 5 is a transverse section taken upon the line 5-5 of Figure 1.

Referring now to the drawing in detail

wherein like numerals of reference indicate corresponding parts throughout the several views, the wrench structure which is indicated as a whole by the numeral 1 comprises, as shown a pair of handle shanks 2 and 3 each of which is relatively long. These handle sections are arranged in juxtaposition and have their opposing and contacting faces flat as shown. At one end of each of the members 2 and 3 there is formed the heads 4 and 5 respectively each of which heads are relatively broad and in the present instance as shown is substantially semi-circular.

It is of course to be understood that applicant does not limit himself to a head structure 65 of semi-circular formation but merely shows this form for illustrative purposes.

The heads 4 and 5 carry, respectively, the jaw members 6 and 7, each jaw section being mounted upon its respective head and at one side thereof so that when the handle shanks 2 and 3 are placed in side by side relation the working faces 8 of the jaws will be opposed.

70 Each of the jaw sections 6 and 7 is of a thickness substantially equal to the thickness of the two handle members and each therefore has one side extending a substantial distance beyond one face of its supporting head thus forming the projecting shoulder 9 which 75 overlies and slides upon the top of the head of the adjacent handle shank as is clearly illustrated in Figure 2.

The two members of the wrench structure are held in adjustable relation by a dove-tail 85 connection, one face of one member, as for example the member 2 being provided, upon the inner face, preferably across the head thereof, with the transversely extending dove-tail ribs 10, the opposing face of the other member being provided with receiving dove-tailed slots or grooves 11. The two members are thus permitted to move laterally with respect to one another but are held 90 against respective longitudinal movement.

95 In order to limit the degree of movement of the two members which make up the wrench structure the head of one member, as for example the head 4 is provided with or carries an inwardly extending movement 100

limiting pin 12 which projects into a slot 13 formed in the inner face of the opposing head member 5, this slot extending substantially half way across the head face as clearly shown in Figure 5 of the drawing.

5 The slot 13 is arranged outwardly of and in parallel relation to one of the grooves 11, and it opens at its inner side through the outer wall of such groove. The inner wall of the slot 13 constitutes a stop with which the pin 12 cooperates to limit the opening movement of the doors 6 and 7.

10 From the foregoing it will be readily seen that the bringing together of the jaw sections 6 and 7 limits the relative movement of the two members of wrench in one direction and the contacting of the pin with the inner end 15 of slot 13 limits the movement of the members in the opposite direction or in opening movement.

20 Having thus described my invention what I claim is:

A wrench comprising a pair of elongated sliding bodies arranged in contact with each 25 other, jaws carried by corresponding ends of the bodies and extending longitudinally and inwardly from the same, one body being provided with transversely extending dove-tail grooves and with a slot having its inner 30 end closed, the slot being arranged outwardly of and parallel to one of said grooves and opening through the bottom wall of such groove, dove-tail ribs extending transversely of the other body and slidably arranged in 35 said grooves, and a pin extending through said other body into said slot and cooperating with the end wall thereof to limit the opening movement of the jaws.

In testimony whereof I affix my signature.
